UNITED STATES PATENT OFFICE.

FRANK A. DONALDSON, OF ST. PAUL, MINNESOTA.

AIR CLEANER.

Application filed November 12, 1921. Serial No. 514,628.

To all whom it may concern:

Be it known that I, FRANK A. DONALDSON, a citizen of the United States, residing at St. Paul, in the county of Ramsey and State 5 of Minnesota, have invented certain new and useful Improvements in Air Cleaners; and I do hereby declare the following to be a full, clear, and exact description of the invention, such as will enable others skilled in 10 the art to which it appertains to make and use the same.

My present invention relates to air cleaners for use in connection with the carburetors of internal combustion engines and is in 15 the nature of a modification of or improvement on the air cleaner disclosed and broadly claimed in my Patent #1,405,399.

Generally stated, the invention consists of the novel construction, arrangement and 20 combinations of parts hereinafter described and defined in the claims.

The present invention, in common with the invention of my prior application, employs a centrifugal or so-called "cyclone" 25 acting dust collector for primarily removing most of the dust from the air.

The present invention, however, simplifies somewhat the construction illustrated in the drawings of my prior application and provides 30 certain novel and important distinctive features of improvement as will herein-after more fully appear.

In the accompanying drawings, which 35 illustrate the invention, like characters indicate like parts throughout the several views.

Referring to the drawings:

Fig. 1 shows the cleaner chiefly in vertical section but with some parts in full; and

Fig. 2 is a perspective of the filter-containing member removed from the casing.

The casing of the cleaner is made up of a lower truncated conical lower section or shell 32 provided at its bottom with a detachable dust-collecting jar 33 and baffle plate 34, which may be of any suitable form 45 but which, as shown, is substantially pyramidal in shape and is connected to the casing 32 at four corners and in a manner that leaves dust passages adjacent to the shell.

The shell 32 has an annular top plate 36 50 formed with a threaded neck 37 adapting it to be screwed into a threaded portion of an upper case section 38, which latter, as shown, has a lateral air outtake tube or 55 passage 39. In this arrangement, a filter 40, preferably a compact body of hair, is placed

in a large air tube 41, the upper portion of which affords a collar and the depending portion of which affords an annular air distributor or skirt. This tube 41 is removable with the filter when the lower case section 32 is unscrewed from the upper case section 38; and, to support said tube and filter in working position, said tube is provided with an upstanding sleeve 42 that is adapted to 60 rest loosely upon the upper end of the threaded neck 37. The jar or dust receptacle 33 is made readily removable from the bottom of the shell 32 and this, as shown, is afforded by coarse threaded engagement. 65

The shell 32, above the bottom of the skirt portion of the tube 41, is provided with tangential air intake ports 35, preferably formed by partly severed inwardly pressed lips that cause the inwardly drawn dust-laden air to take up a whirling motion immediately around said skirt. Thus, the dust-laden air is immediately caused to whirl, so that the dust will be thrown by centrifugal force against the walls of the shell 32 and will be given a whirling motion toward and finally to the bottom of the shell and from thence into the dust receptacle 33. The air from which the greater part of the dust has been precipitated will be drawn upward 80 through the air tube 41 and the remaining dust will be removed therefrom by the filter 40, so that only very clean air will reach the upper air chamber or compartment 85 formed within the upper case section or shell 38.

This filter, the preferred form of which is here illustrated, while of very simple construction and of low manufacturing cost, has, in practice, been found highly efficient 95 as a dust collector and air cleaner for use in connection with internal combustion engines. Of course, in practice, the air outlet tube 39 will be connected to the carburetor of such engine so that only clean air will be delivered to the carburetor and from thence to the engine cylinders. 100

What I claim is:

1. A combined gravity and filter-operating dust collector comprising a casing provided at its upper portion with circumferentially spaced air intake passages and provided at its bottom with a dust receptacle, an upper shell to which said casing is detachably secured and from which it depends, 105 and a filter-equipped tube of considerably less diameter than the upper portion of said 110

casing, applied through the top of said casing and extended within said casing to a plane below the air intake passages thereof.

2. A combined gravity and filter-operating dust collector comprising an inverted truncated conical casing having circumferentially spaced tangential air intake passages near its top and provided with an upstanding threaded neck of less diameter than its
- 5 top portion, an upper shell having a threaded portion into which the threaded sleeve of

said casing is screwed, a dust receptacle detachably applied to the contracted lower end of said casing, an air tube detachably applied in the threaded neck of said casing 15 and extended within said casing to a plane below said air intake passages, and a body of filtering material in said air tube, removable therewith from said casing when said casing is detached from said upper shell. 20

In testimony whereof I affix my signature.

FRANK A. DONALDSON.
